Walter W. Stanard, of Buffalo, N.Y.

Assignor to

Sherman S. Jewett & Francis H. Root, of same place,
Letters Patent No. 1365, dated April 15, 1863,

The schedule referred to in these Letters Patent and making part of the same.

To all whom it may concern,

Be it known that I, Walter W. Stanard, of the City of Buffalo, County of Erie, and State of New York (assignor to Sherman S. Jewett and Francis H. Root, firm of Jewett & Root, of the same place) have invented or produced a new and original design for Cooking Stoves, which I denominate "Illinois" and I do hereby declare that the following is a full and clear description thereof, reference being had to the accompanying photographic plates and the letters of reference marked thereon, in which-

Fig. 1. represents the upper front plate with doors.

Fig. 2. the lower front plate with doors, and

Fig. 3. the side plate with doors.

The upper front plate Fig. 1. has two pair of sliding doors. The surface of the upper doors is "ogee" form, as is also that part of the plate on which they slide. They are surrounded by plain moulding a, and have a central embossed ornament b.

The jambs on each side have an ornament c, of reticulated and carved work.

The lower doors are surrounded by mouldings d, similar to the upper doors and have a carved ornament e, in their panels. The panels in the jambs have a central star pointed embossed ornament f.

In the lower front plate Fig. 2. g, are two small doors at its bottom having an embossed ornament h, on their panels and surrounded by a plain bead moulding i. j is a carved ornament over the doors and k, ornaments at the sides of the plates.

Dec. 1565

The side plate Fig. 3, is surrounded by a plain beaded moulding k, with carved pointed moulding l, at the bottom. The large oven door m, is surrounded by quarter round and ogee mouldings n, its upper corners being rounded off. It has a large embossed leaf o, in the centre with carved or embossed junk p.

q. Is a band of small leaves and stems between the door and the back edge of the plate.

The small oven door r, and fire door s, are surrounded by mouldings similar to those surrounding the large oven door and have carved or embossed ornaments t - u, in their panels.

Below the large oven door is the frame of the plate "Illinois" in large embossed letters.

The plates will show the exact and detailed configuration of the various ornaments described and their arrangement in regard to each other.

I claim the within described ornamental devices for the decoration and embellishment of the plates of a certain size arranged and combined as represented in each of the accompanying photographic plates Fig. 1, 2, & 3.
